BUFFING WHEEL SECTION

Elisha W. Hall, Scituate, Mass.

Application July 17, 1951, Serial No. 237,171

5 Claims. (Cl. 51—193)

1

This invention relates to buffing wheels and in particular to a so-called section adapted to be assembled on a spindle with other like sections to form a wheel of the desired length of face. The object of the invention is to provide in such a section inbuilt means whereby by virtue of the way in which the sections are assembled, different densities of the working face of the wheel may be obtained. For this purpose obverse and reverse sides of the section at a location inwardly of its periphery are provided with bearing parts which are differentially formed on the sides respectively, so that when two like sides of two sections are presented one to the other, the central planes of the two sections will be spaced by a determined amount, whereas if unlike sides are presented one to the other, the spacing will be different. I have used the words "obverse" and "reverse" which, however, merely are a convenient identification of the two sides of the section, to avoid the uncertainties of referring to "one" and "the other," but the words are not otherwise significant.

The invention will be well understood by reference to the following description taken in connection with the accompanying drawings, wherein:

Fig. 1 is a side elevation of the section showing the obverse side;

Fig. 2 is a similar view showing the reverse side;

Fig. 3 is a fragmentary section in a radial plane showing the confronting sides when two like faces are apposed to each other;

Fig. 4 is a similar view showing two unlike faces apposed to each other; and

Fig. 5 is a diagrammatic view to illustrate the bearings provided between the two sections when unlike faces are apposed to each other.

Referring to the drawing there is there shown a buffing wheel section of known type, generally in the form of a thin cylindrical disc and comprising a relatively rigid central portion including a hub 10 (Figs. 3 and 4), conveniently formed of chipboard, pierced at 12 to receive the spindle and encircled by an annular mass of abrading material 14, herein formed of a number of plies of fabric so arranged as to present ruffles or pleats at the periphery of the section. Side plates 16 of thin vulcanized fiber overlie the sides of the hub and the inner portion of the abrading mass. These parts may be secured together by suitable adhesive. In assembling and uniting the parts under pressure, an annular ridge 18 may be formed in the sideplates to interlock with

2

the abrading means. When a number of these sections are assembled side by side and clamped on a spindle, the clamping plates usually grip the assembly at the inner part of the buffing annulus 14, conveniently substantially at the location of this ridge 18. A section having a construction as so far described is not new and it serves merely as an illustration of one kind of section to which the invention may be applied.

In the example of the invention shown, the obverse face of the section as seen in Fig. 1 is provided with a series of regularly spaced projections 20_o and the reverse face of the section as seen in Fig. 2 with a series of regularly spaced projections 20_r. I indicate conventionally in Fig. 1 the color black on side plate 16 of the obverse side and in Fig. 2 the color red (suggestive of "reverse") on the reverse side, further to distinguish arbitrarily the two faces. In practice moreover, the two side plates 16 may actually be colored in contrasting colors for ready differentiation.

In the present example the various projections are identical in size and shape and their position is at the same radial distance from the center, their differentiation for purposes of the invention being obtained by their relative circumferential spacing which implies a difference in number, there being in the example shown twenty on the obverse side and sixteen on the reverse side.

The projections 20_o and 20_r are here shown as circular and more or less dome-shaped embossments formed by suitable dies when the section is made under axial compression. Herein they are shown as arranged on the ridges 18 which is not significant, since so far as the correlation of the projections is concerned, the top of this ridge may be considered merely as a part of the end surface of the inner portion of the section. It may be noted however that when formed as hollow embossments as herein opposite the inner portion of the abrading mass 14 a portion of the latter is pressed into the concavities of the embossed projections and forms an interlock resisting both radial and circumferential displacement and that this mass of material supports the wall of the hollow projections against axial compression exerted thereon when the sections are clamped.

The size and spacing of the projections on the obverse side (see Fig. 1) are such that when the obverse sides of two like sections are presented one to the other with the projections out of line, then as illustrated in Fig. 3, the projections 20_o on one will enter between the projections 20_r on

the other. In other words, the projections will axially overlap. In the present instance, partly because of the dome form of the sections which causes them to decrease in circumferential width outwardly, the overlapping is complete and the ends of the projections rest on the base surface from which the projections of the opposing section arise. I consider such a construction preferable to one wherein tapered projections nesting would bear on one another laterally with clearances at the crests. The arrangement may be described by saying that the sum of the circumferential widths of the projections is not greater than one-half the circumference so that the intervening spaces permit the entry thereinto of the projections of an adjacent section. The space between the central planes of two assembled sections is thus in the example shown twice half the thickness of the sections as measured between the crests of the ridges 18 plus the height of a projection 20.

The projections 20r of the reverse side are of the same size as the projections 20o but spaced further apart circumferentially because their number is smaller. Clearly they will similarly overlap axially when two reverse sides are presented to each other. Except for the reference numerals Fig. 3 would represent such an arrangement.

To provide for a different spacing when a reverse and observe side are apposed, the circumferential length of the spaces intervening between adjacent projections 20r on the reverse side is greater than that between adjacent projections 20o on the obverse side, but less than the sum of such space on the observe and the circumferential width of a projection 20o adjacent thereto and the circumferential width of two adjacent projections 20o on the observe side and of the space intervening between them is greater than the circumferential width of the space between two adjacent projections 20r on the reverse side. This may be explained further by reference to the diagram, Fig. 5, in which the projections 20o are shown in full lines and dot-and-dash lines illustrate the outlines of projections 20r superposed thereon. At the half-past ten o'clock position at the left of the figure the dot-and-dash projection 20r is substantially centered between two projections 20o and is in line with the space between them, and if we were concerned solely with these three projections the overlying projection could pass in between the other two as is seen in Fig. 3. Passing clockwise however to the next adjacent projection 20r shown in dot-and-dash lines, it will be seen that this gains on the full line projections 20o and overlaps to a certain extent the underlying projection 20o toward its left. The next projection 20r in the series gains further and at the twelve o'clock position the projections 20r and 20o are in alignment. The next projection 20r passes further across the face of the projection 20o immediately beneath the same and at the half-past one position the cycle is complete and the projection 20r is centered between two of the projections 20o. This repeats itself around the circle in four complete cycles, two of which are illustrated, the projections at the 9, 12 and 3 o'clock positions being in alignment and those immediately adjacent thereto at either side being in partially overlapping position. If we change the relative position of the two sections as by a movement equivalent to a slight clockwise revolution of the projections 20r

in Fig. 5, the projections in the 12 o'clock position will no longer be exactly aligned. The amount of overlap of the pair to their right will be decreased, but that of the pair to the left increased and overlap may commence at the groups formerly completely out of alignment. When the movement has continued through an arc of $22\frac{1}{2}^\circ$ the relative position of the two groups considered as such is the same as in the figure. By virtue of this arrangement when the obverse side and the reverse side of two adjacent sections are presented one to the other the projections cannot nest as when like sides are presented to one another and as is seen in Fig. 3, but bearings are provided which hold the sections apart as seen in Fig. 4, and consequently provide for a lesser density of the wheel at the periphery. The increase in spacing in the example shown is the altitude of the projections.

The arrangement may be apprehended in terms of the number of projections, herein twenty on the obverse and sixteen on the reverse. The gaining or hunting effect described in connection with Fig. 5 is obtained when the least common multiple of the numbers of projections on the two sides contains relatively prime factors. If these were the only two factors the two numbers would be relatively prime and the gain or hunting effect would occur gradually throughout the circumference. Preferably as here the two numbers also have a common factor of three or more, herein four. In this instance the displacement of the elements of one series relative to the other occurs for each group of five projections 20o and four projections 20r, five and four being the relatively prime factors of twenty and sixteen respectively. This cycle occurs four times in the circumference and therefore the relation of apposed projections is identical at distances 90° apart and the bearing of sections one on another is thus balanced throughout the circumference.

In assembling a wheel from these sections we may put like faces together throughout, producing a relatively dense periphery or unlike faces throughout, producing a relatively soft periphery, or the spacing may be varied to provide a wheel with a relatively soft section which is sometimes desired.

I am aware that the invention may be embodied in other specific forms without departing from the spirit or essential attributes thereof, and I therefore desire the present embodiment to be considered in all respects as illustrative and not restrictive, as is in fact clear in several matters from the description itself. Reference is to be had to the appended claims to indicate those principles of the invention exemplified by the particular embodiment described and which I desire to secure by Letters Patent.

I claim:

1. A buff section adapted for assembly on a spindle side by side with other like sections to form a buffing wheel said section comprising a relatively unyielding center and an annulus of abrading material encircling its periphery and anchored thereto, the center having on its obverse and reverse sides at substantially the same distance radially from the center annular series of spaced axially extending projections, at least outer portions of the projections extending over less than one-half the circumference whereby the projections on the obverse sides of two sections or those on the reverse side may nest with at least partial axial overlapping, the projections

on the obverse side and those on the reverse side being differentially spaced to provide circumferential overlapping of projections of two adjacent sections assembled obverse to reverse.

2. A buff section adapted for assembly on a spindle side by side with other like sections to form a buffering wheel said section comprising a relatively unyielding center and an annulus of abrading material encircling its periphery and anchored thereto, the center having on its obverse and reverse sides at substantially the same distance radially from the center annular series of spaced axially extending projections, the circumferential extent and spacing of the projections in each series being such as to provide, when a side of a section is presented to the like side of a like section, for entry of the projections of one section between those of the other with at least partial overlapping in the axial direction, the number of projections on the obverse being 15 different from the number on the reverse, the two numbers being different and their least common multiple having two relatively prime factors.

3. A buff section adapted for assembly on a spindle side by side with other like sections to form a buffering wheel said section comprising a relatively unyielding center and an annulus of abrading material encircling its periphery and anchored thereto the center having on its obverse and reverse sides at substantially the same distance radially from the center annular series of spaced axially extending projections, the circumferential extent and spacing of the projections in each series being such as to provide, when a side of a section is presented to the like side of a like section, for entry of the projections of one section between those of the other with at least partial overlapping in the axial direction, the number of projections on the obverse being 20 different from the number on the reverse, the two numbers having a common factor at least as great as three and other factors respectively 25 which are relatively prime.

4. A buff section adapted for assembly on a spindle side by side with other like sections to form a buffering wheel said section comprising a relatively unyielding center and an annulus of abrading material encircling its periphery and anchored thereto, the center having on its obverse and reverse sides at substantially the same distance radially from the center annular series of spaced axially extending projections, the projections of each series being regularly spaced, the sum of circumferential widths of the projections of each series at least at the crests being no greater than half a circumference, and the circumferential length of the spaces intervening between adjacent projections on the reverse side being greater than that between adjacent projections on the obverse side but less than the sum of such a space on the obverse and the circumferential width of a projection adjacent thereto.

5. A buff section adapted for assembly on a spindle side by side with other like sections to form a buffering wheel said section comprising a relatively unyielding center and an annulus of abrading material encircling its periphery and anchored thereto, the center having on its obverse and reverse sides at substantially the same distance radially from the center annular series of spaced axially extending projections, the projections of each series being regularly spaced, the sum of circumferential widths of the projections of each series at least at the crests being no greater than half a circumference, the circumferential width of two adjacent projections and of the space between them on the obverse side being greater than the circumferential width of the space between adjacent projections on the reverse side.
